US0D1081664S

(12) **United States Design Patent** (10) **Patent No.:** **US D1,081,664 S**
Chen (45) **Date of Patent:** **** Jul. 1, 2025**

(54) **KEYBOARD**

(71) Applicant: **Dongguan Lingjie Electronics & Technology Co., Ltd.**, Dongguan (CN)

(72) Inventor: **Yangde Chen**, Shaoyang (CN)

(73) Assignee: **Dongguan Lingjie Electronics & Technology Co., Ltd.**, Dongguan (CN)

(**) Term: **15 Years**

(21) Appl. No.: **29/965,768**

(22) Filed: **Sep. 29, 2024**

(51) LOC (15) Cl. **14-02**

(52) U.S. Cl.

USPC **D14/392**

(58) **Field of Classification Search**

USPC D14/247, 331, 333, 338, 346, 387-401, D14/406, 429, 455-457; D18/1-2, 4.2, 7, D18/12.2, 52; D21/324

CPC B41J 5/00; B41J 5/10; B41J 5/12; G06F 3/021; G06F 3/0216; G06F 3/0219; G06F 3/02

(57) **CLAIM**

The ornamental design for a keyboard, as shown and described.

DESCRIPTION

FIG. 1 is a front, right and top perspective view of a keyboard, showing my new design;

FIG. 2 is a rear, left and bottom perspective view thereof;

FIG. 3 is a front view thereof;

FIG. 4 is a rear view thereof;

FIG. 5 is a left-side view thereof;

FIG. 6 is a right-side view thereof;

FIG. 7 is a top plan view thereof; and,

FIG. 8 is a bottom plan view thereof.

The broken lines shown in the drawings illustrate portions of the keyboard that form no part of the claimed design.

1 Claim, 8 Drawing Sheets
